UNITED STATES PATENT OFFICE.

FRANK KRABAL, OF CHICAGO, ILLINOIS.

GAS-BURNER.

No. 899,600.

Specification of Letters Patent. Patented Sept. 29, 1908.

Application filed April 24, 1907. Serial No. 370,041.

To all whom it may concern:

Be it known that I, FRANK KRABAL, a citizen of the United States, residing at Chicago, in the county of Cook and State of Illinois, 5 have invented certain new and useful Improvements in Gas-Burners, of which the following is a specification.

This invention relates to improvements in gas burners for illuminating purposes and 10 has for its object the production of a burner that will become automatically closed in case the light is blown out instead of being turned out by shutting off the gas by the ordinary cock in the pipe adjacent to the burner.

15 A further object of the invention is to produce a burner that will provide greater safety against accidents from curtains, hangings or other inflammable materials coming into contact with the flame of the burner.

20 With these objects in view and further objects and advantages that will appear as the nature of my invention is more fully disclosed, I have constructed the novel and useful burner herein to be described and illustrated by reference to the accompanying drawing which shows one embodiment of my invention by an enlarged longitudinal sectional view.

Referring to the drawing: 1 represents the 30 tip of lava or other refractory material upon which the gas burns.

2 represents the burner tube which holds the tip 1, in its upper end and terminates below in a ground spherical portion 3, which is 35 fitted accurately in the upper part of the correspondingly formed cup or base portion 4. The cup or base portion 4, terminates below in a cylindrical portion 5, which is provided with a threaded recess 6 whereby it may be 40 screwed to the usual threaded terminal portion of the chandelier or fixture on which it is to be used. The passage 7 is provided in the central portion of the cup or base to communicate with a corresponding passage 8 45 in the bottom of the spherical portion 3, of the body in such manner that when the body 2, is in an upright or vertical position there may be free ingress of gas from the fixture below. The upper portion of the cup or base 50 4, is threaded externally for the internally threaded collar 9 which serves to secure the spherical portion of the body in the corresponding portion of the cup or base, but without pressure or unnecessary friction 55 therein.

The operation of the burner is as follows.

The body of the burner is set in an upright position and the gas turned on at the stop-cock in the fixture. The gas then passes through the passages 7 and 8 to the body of the 60 burner and is ignited at the tip 1, in the usual manner. The body of the burner being neatly poised on its spherical portion will be easily deflected by any light pressure against its upper end, and any attempt to extinguish 65 the light by blowing it out will displace the upper part of the burner to the position shown by the dotted lines, thereby destroying the alignment of the passages 7 and 8 and cutting off the gas, the passage 8 being displaced as 70 shown by dotted lines at 10. The spherical contact between the upper and lower portions of the burner is adjusted with such nicety that the upper portion will be deflected and the gas cut off by much less violent blowing than 75 would be required to extinguish the light by the breath alone. It is therefore impossible to extinguish the light without at the same time preventing any further flow of gas until the upper portion of the burner is again 80 placed in an upright position. From the above it is also apparent that any contact of draperies, curtains, hangings or any other thing which might become ignited from an ordinary burner would, in my improved 85 burner, instantly extinguish the flame and would do so in less time than would be required for their ignition unless they were of a very highly inflammable character. This feature of safety I regard as of great value 90 in my invention, but the collar 9 may be so fitted as to admit of being screwed down against the spherical portion 3 of the body thereby making the upper and lower portions practically integral and converting the 95 burner substantially into one of the ordinary kind without any disadvantages on account of its special construction.

Having now fully described one of the embodiments in which my invention may be 100 carried out and expressly reserving the right to any and all applications of the principle thereof, what I claim is:

1. In a device of the class described, a base portion having a hemispherical socket in 105 its upper end, in combination with a burner tube having a spherical lower end resting in said socket and normally held therein by gravity, said burner tube and said base portion having ports adapted to register when 110 the burner tube is in vertical position and to close when the same is in inclined position,

- and means to prevent separation of said base and said burner tube, said means normally exerting no pressure upon the ball and socket members, substantially as described.
- 5 2. In a device of the class described, a base portion having a hemispherical socket in its upper end, in combination with a burner tube having a spherical lower end resting in said socket and normally held therein by
- 10 gravity, said burner tube and said base portion having ports adapted to register when the burner tube is in vertical position and to close when the same is in inclined position, a collar threaded on said base portion and hav-

ing an inturned flange surrounding the upper 15 portion of said spherical end and adapted to prevent displacement of the ball from its socket, said flange normally exerting no pressure upon the ball and socket members, substantially as described.

20 In testimony whereof I have signed my name to this specification in the presence of the two subscribing witnesses.

FRANK KRABAL.
